PRESS

Robert P. Frost, Redding, Calif.

Application June 28, 1944, Serial No. 542,578

3 Claims. (Cl. 100—70)

This invention relates in general to an improved press, and in particular the invention is directed to, and it is an object to provide, a relatively light-duty press adapted for general utility, mechanical pressing operations in garages, repair shops, machine shops, or the like, where a heavy-duty press is unnecessary.

Another object of this invention is to provide a general utility press, as above, which is simple in structure, inexpensive to manufacture, and employs a conventional hand actuated hydraulic jack as the power means.

An additional object of the invention is to embody, in the press, a novel form of vertically adjustable work supporting bed whereby the press, which has limited vertical movement of the pressing head, can be adjusted to accommodate work of substantial variance in height.

It is also an object to provide a press which is exceedingly practical and effective for the purpose designed.

In the drawing similar characters of reference indicate corresponding parts in the several views:

Figure 1 is a side elevation of the press.

Figure 2 is an end elevation of the press.

Figure 3 is a cross section taken immediately above the work supporting bed.

Referring now more particularly to the characters of reference on the drawing, the press comprises a frame which includes a floor supported base 1 from which a pair of relatively widely spaced end posts 2 upstand in rigid relation; the end posts 2 each comprising a pair of flat plates 3 disposed in spaced but parallel facing relation. The plates 3 are set edgewise relative to the ends of the press.

At their upper ends the posts 2 are connected by a rigid, horizontal top beam 4, and a flat, work engaging head 5 is disposed horizontally below top beam 4 in symmetrical relation thereto, and centrally between the end posts 2. Guide rods 6 are fixed on and upstand from the head 5 adjacent the corners thereof, said guide rods projecting through vertically elongated guide sleeves 7 formed on the top beam 4; one pair of guide rods being disposed on one side of the top beam and the other pair on the other side of said beam. Tension or pull-back springs 8 connect between the corners of the head 5 and corresponding points on the top beam 4; said springs being parallel to the rods 6.

The head 5 is normally disposed some distance beneath the top beam 4, and a hydraulic jack 9 of the hand-actuated type is seated on the head 5 and engages between the latter and the top

beam 4; such jack including an actuating lever 10.

Actuation of the jack 9 by means of the lever 10 in a direction to extend the jack will cause positive and forceful downward movement of the head 5, and such movement is guided by the rods 6. When the jack is released the pull back springs 8 will of course return the head 5 to its raised or starting position.

10 The work supporting bed for the press comprises the following arrangement:

An elongated, open rectangular frame, indicated generally at 11, is disposed horizontally below the head 5 with the end posts 2 projecting 15 in guiding relation through opposite end portions of the frame 11, as clearly shown in Fig. 3. The frame 11 includes horizontally aligned side beams 12 of channel iron, which beams are disposed on edge whereby the upper flanges of said beams 12 form a work supporting bed. The side beams 12 are connected by end beams 13 to complete the frame 11. The frame 11 is supported, in vertically adjustable relation to the end posts 2, by means of cross pins 14 which engage in transversely aligned, outwardly opening notches 15 formed in the plates 3 of each post; there being matching vertical rows of said notches in the plates of each post. The cross pin 14 corresponding to each post is of a length to project 20 beyond both sides of the post whereby to engage and support the frame 11 from beneath; the pins 14 always being adjusted to the same elevation so as to maintain the frame 11 horizontal.

When the press is in use the work is supported 25 on top of the side beams 12 for engagement by the work engaging head 5 upon downward movement of the latter. If desired, the head 5 may include a centrally disposed, downwardly projecting push-out pin 16, preferably removable from the head 5.

As the work supporting bed comprises spaced 30 side beams 12 work with an axially projecting portion, as for example a wheel 17 having a shaft 18 projecting therefrom, as shown in dotted lines in Fig. 1, can be supported effectively from said bed for engagement of the head 5 with such work.

In the illustration as in Fig. 1 the shaft 18 will 35 be engaged by the head 5 upon downward movement of the latter and will be pressed downwardly through the wheel 17; the spacing of the side beams 12 permitting the lower portion of the shaft to depend without obstruction and for 40 downward movement.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as set forth herein.

Having thus described my invention, what I claim as new and useful and desire to secure by Letters Patent is:

1. A press comprising an upstanding frame including a top beam, a work supporting bed mounted on the frame in spaced relation below the top beam, a work engaging head disposed between the top beam and work supporting bed, guide rods projecting upwardly from the head, guide sleeves on the top beam through which said

rods slidably extend, a pull-back spring between the top beam and head, and a hand actuated jack engaged between said head and top beam.

2. A press comprising an upstanding frame including a top beam, a work supporting bed mounted on the frame in spaced relation below the top beam, a work engaging head disposed between the top beam and work supporting bed, guide rods projecting upwardly from the head, guide sleeves on the top beam through which said rods slidably extend, a pull-back spring between the top beam and head, and a hand actuated jack engaged between said head and top beam; said head being rectangular and said rods being disposed adjacent the corners thereof.

3. A press as in claim 2 including a pull-back spring connected between the top beam and head at each corner of the latter; said springs being parallel to and adjacent corresponding rods.

ROBERT P. FROST.
